United States Patent Office.

WILLIAM J. ALEXANDER, OF ROLLING PRAIRIE, INDIANA.

Letters Patent No. 71,675, dated December 3, 1867.

IMPROVEMENT IN GATES.

The Schedule referred to in these Letters Patent and making part of the same.

TO ALL WHOM IT MAY CONCERN:

Be it known that I, WILLIAM J. ALEXANDER, of Rolling Prairie, in the county of La Porte, and State of Indiana, have invented a new and useful Improvement in Gates; and I do hereby declare that the following is a full, clear, and exact description of the construction and operation of the same, reference being had to the annexed drawings making a part of this specification, in which—

Figure 1 represents the gate closed, and

Figure 2 represents the gate elevated and open.

A represents the gate; B represents post to which the gate A is attached; C represents brace in the elevating frame; D D represent plates, which are stationary; E represents brace attached at base of the post B, and to which the outside plate D is attached at the top opposite the top of the post B; F represents the chain which is attached to the gate A, and runs over a pulley in the frame above the brace C; G represents the weight which is attached to the end of the chain F, which chain F runs on a pulley in the top of the brace E; H represents the hinge which passes partly around the post B; this may be sawed out of wood, and the post B need only to be rounded where the hinge H is placed thereon. I represents a notched pin placed in the outside end of the inside plate D, and through which the chain F is placed, so that when the gate A is thrown open, it is drawn shut by the weight G; or, in case it is desired to have the gate A remain open, by removing the pin I, the gate A is held open by the weight G. J represents a pin, which is passed through the bars of the inside of the frame, at the lower end, which are on either side of the gate A, and through the three top bars of the gate A are holes near the centre of said gate A, through which the pin J passes. By removing the pin J the gate A is elevated to any height desired, by means of the weight G, so that no lifting is necessary to elevate the gate A; and the gate A may be left at any height desired by inserting the pin J, and may swing free from snow or mud, or may be left so that sheep or smaller animals may pass under, and still keep out horses and cattle. The outside plate D is so arranged that it cannot be moved while the inside plate D works upon a pin in the top of the post B. There is no strain upon the gate A; all the weight of the gate A is upon the braces C and E, which are braced upon the post B. By placing the braces C and E and the weight G in this manner, they are out of the way of a load passing through. There need be no bolts used in the construction of the gate A, as there is no strain thereon.

What I claim as my invention, and desire to secure by Letters Patent, is—

The gate A, the braces C and E, the chain F, with the weight G and pin I, as substantially arranged and set forth in the foregoing.

WILLIAM J. ALEXANDER.
